UNITED STATES PATENT OFFICE.

JOHN E. BICKNELL, OF CLEVELAND, OHIO.

APPARATUS FOR SEPARATING OIL-VAPORS.

SPECIFICATION forming part of Letters Patent No. 313,979, dated March 17, 1885.

Application filed May 22, 1884. (No model.)

To all whom it may concern:

Be it known that I, JOHN EDWARD BICKNELL, of Cleveland, in the county of Cuyahoga and State of Ohio, have invented a new and Improved Apparatus for Separating Oil-Vapors, of which the following is a full, clear, and exact description.

My improvements relate to apparatus for the separation of the different grades of oil contained in one common stock or kind while in a vaporous state; and the invention consists in a special construction having the object to insure the certain condensation of the vapors of the heavy oil, while the vapors of lighter specific gravity pass off separately, and also in means for accurately regulating the temperature of the condenser at all times, as hereinafter described and claimed.

Reference is to be had to the accompanying drawings, forming part of this specification, in which similar letters of reference indicate corresponding parts in both the figures.

Figure 1 is a sectional elevation of the apparatus, and Fig. 2 is a vertical section of the condenser in a plane at right angles to Fig. 1.

The condensing-vessel A is an iron tank of flattened tubular form and of suitable length, having a separate chamber, a, at the top and chamber b at the bottom, formed by horizontal plates or partitions b'. c c are pipes of sinuous form, or made with quick bends, extending from the top chamber, a, to the lower chamber, b, and through the plates b'. d is a trapped pipe from chamber b. h is a pipe from chamber a to a tank, B. i is a safety-valve. k k are water-inlet pipes entering near the upper part of the condenser, and having perforated ends for spraying the water. l is a steam-pipe entering the vessel A, having separate branches l' l'', for supplying either superheated or wet steam. m is a pipe for drawing off water of condensation, and q is the pipe for supplying the oil-vapors to chamber b. The tank B, which is for the second separation, has a trapped outlet-pipe, n, from the bottom, a pipe, o, from the top, which will pass to a water-box, and a steam-supply pipe, p, that connects with a perforated coil on the bottom of the tank. The vapors from the still enter chamber b by the pipe q, from whence they rise naturally into pipes c. By the sinuous form and sharp bends of

the pipe the particles are caused to continually change their course, and are brought into intimate contact with the sides of the pipes, which are kept at proper temperature, as hereinafter specified. The heavy vapors, or those of oils which vaporize at a higher temperature than that of the pipes, are quickly condensed and return to chamber b, whence they pass out by pipe d. The lighter vapors, or those whose vaporizing-point is lower than the temperature of pipes c, pass upward and out by pipe h to tank B, which they reach in a condensed condition, and are heated by wet steam, supplied by pipe p, into oil, which covers the perforated coil on the bottom of the tank. The agitating and heating of the oil by the steam vaporizes and drives off the lighter products by pipe o into a water-box, while the heavier portions, which are of too high a vaporizing-point to be vaporized by steam, but too low to have been condensed in pipes c, go by pipe n to a cooler.

In first starting the apparatus the condenser A is supplied with superheated steam, in order to obtain a temperature high enough to cause the first separation; otherwise the vapors of light specific gravity will condense and go out by pipe d with the heavy oil. As the vapors increase in temperature and quantity the pipes c are heated more highly, and it is necessary to use wet instead of dry steam to check the rising temperature, so that the heavy vapors may condense, and later it is necessary to use hot and then cold water in order to keep down and properly regulate the temperature of pipes c. This is allowed for by the arrangement of steam-pipes l' l'' and water-pipes k k.

The advantages of this apparatus over others of the same class lie in the perfect separation insured by the accurate regulation of the temperature and the contact of the vapor particles with the condensing-pipes caused by their sinuous form.

Having thus described my invention, what I claim as new, and desire to secure by Letters Patent, is—

1. The condenser A, plates b', and end caps forming chambers b, sinuous pipes c, extending through the condenser into the said chambers, pipes q d, connected with chamber b, pipe h, connected with chamber a, and hot and cold

water pipes leading into the condenser between the two end chambers, substantially as set forth.

2. The combination, with vessel A and pipes 5 *c*, of the water and steam pipes *k k l l f*, substantially as described, for supplying dry or wet steam or water at any temperature for the

purpose of maintaining the condensing pipes at a uniform heat, as specified.

JOHN E. BICKNELL.
